UNITED STATES PATENT OFFICE.

EVALD O. ENGELKE, OF CLEVELAND, OHIO.

ELECTRIC SWITCH.

1,252,417.

Specification of Letters Patent. Patented Jan. 8, 1918.

Application filed March 21, 1917. Serial No. 156,244.

To all whom it may concern:

Be it known that I, EVALD O. ENGELKE, a subject of the King of Sweden, residing at Cleveland, in the county of Cuyahoga and State of Ohio, have invented certain new and useful Improvements in Electric Switches, of which the following is a specification.

This invention relates to improvements in switches designed to make and break electric circuits, the object of the invention being the provision of a device of this character which is effective for the purpose and which can be manufactured at comparative small cost owing to the simplicity of construction and assembling of the parts. With the above mentioned object in view the invention consists in the construction, combination, and arrangement of elements as described in the specification and pointed out definitely in the claims.

To facilitate the explanation of the invention the accompanying drawings are made a part of the specification, similar characters of reference being employed to designate similar parts.

In the drawings Figure 1 is a plan view of the improved device with the cover, operating button, and a spring element removed.

Fig. 2 is a section on line 2—2 of Fig. 1, also showing the parts that are omitted in Fig. 1.

Fig. 3 is a section on line 3—3 of Fig. 1.

Fig. 4 is a top plan view of a certain element of the device, detached, and Fig. 5 is a section on line 5—5, Fig. 4, Fig. 6 being an underside view and Fig. 7 a section on line 7—7 of said element.

Fig. 7^a is a plan view of a metallic contact member hereinafter identified.

Figs. 8, 9, and 10 are, respectively, plan, edge, and sectional views of one of the elements detached, Fig. 10 being a section on line 10—10 of Fig. 8.

Figs. 11 and 12 are detail views of the operating spindle.

Fig. 13 is a perspective view of one of the contact members, and Fig. 14 is a plan view on a reduced scale illustrating a multiple switch.

In my simple and economical construction I employ a base member 1 of porcelain or other suitable insulating material. The said member 1 is preferably circular and is provided with an annular ledge 1^a, an annular channel 1^b and a central bearing face 1^c.

A disk 2 of suitable insulating material is adapted to bear on the face 1^c, and is provided with a central hole 2^a that registers with a hole 1^d in the member 1. For convenience of explanation the bearing face of the disk 2 will be considered as the bottom face and its opposite as the top face. So considered, the top face of member 2 is countersunk as shown at 2^b to receive a plate 3, the said plate 3 being provided with projections 3^a. The contour of the countersink 2^b fits the contour of the member 3, thus it will be seen that when member 3 is seated in member 2 any annular movement of member 3 will be imparted to member 2, the purpose of which will presently be made clear.

Embedded in a depression 2^c in the bottom face of member 2 is a metallic plate 4, segments 4^a of which project outwardly beyond the periphery of said member 2, the segmental portions 4^a bearing on the shoulders 2^d and thereby preventing annular movement of member 4 independent of member 2. The thickness or depth of plate 4 is the same as the depth of the depression 2^c, therefore when assembled the member 2 and plate 4 bear on the face 1^c, and are adapted to revolve together thereon.

An operating spindle 5, preferably provided with a sleeve 6, is centered in and passes through members 1, 2, 3, and 4 and is retained in its connection therewith by suitable means, such as a split washer 7 in engagement with an annular groove 7^a. The spindle 5 is provided with keys 5^a adapted to engage key-ways 3^b in the member 3 and thereby cause said member 3 to turn with the spindle 5 when said spindle is actuated by manipulating the button 5^b.

Spring contact members or brushes 8 are connected with the base 1 by binding screws 9, located on the ledge 1^a in pairs diametrically opposite, and in such position relative to the revolute members that they will make and break contact with the segmental projections 4^a when said revolute members are rotated. It will readily be seen that through the engagement of the keys 5^a with the member 3, the engagement of member 3 with member 2, and the like relation of member 2 with member 4, when the spindle 5 is turned the member 4 is caused to turn and thereby make and break contact with the brushes 8.

The device is provided with a suitable

cap or cover member 10, and a coiled spring 11 which bears on said cover and on the member 3. The tension of the spring 11 retains the movable elements in operative condition.

It will be noted that the novel construction of the improved switch permits its operation either to the right or left, which is a feature not common to other devices of this character. The switch being operative as above set forth, it is desirable that the member 5^b be firmly attached to the spindle 5. This is provided for as shown in Fig. 12. A shoulder 5^c is formed on the spindle 5, the member 5^d which enters the button 5^b being of less diameter than the body of the spindle. The part 5^d is provided with an eye adapted to receive a tongue 12^a; said tongue being a reduced portion of a blind head screw 12 which is threaded into the member 5^b.

The base member 1 is provided with a countersink 1^e for the terminal of the spindle 5, and also with countersinks 1^f for the binding post retaining nuts 9^a. Electrical connections 13 pass from the binding posts 9 through openings 1^g in the base member 1 to a countersunk channel 1^h in said base.

What I claim and desire to secure by Letters Patent is—

1. An electric switch comprising a base, a rotary spindle mounted in said base, a disk of insulating material mounted on said spindle and having recesses in its upper and lower faces, a plate seated in the upper recess of said disk and rotatably movable therewith, a metallic plate seated in the lower recess of said disk and rotatably movable therewith, segments of said metallic plate extending outside the periphery of the disk, projections on the spindle that engage grooves in the upper plate whereby said disk and plates are rotated, and contact members attached to the base arranged to make and

break contact with the extending segments 45 of the metallic plate as said plate is rotated.

2. In an electric switch the combination of a base provided with a ledge, binding posts on said ledge located in diametrically opposite relation, a rotary spindle mounted 50 centrally in said base, a disk of insulating material mounted on said spindle and bearing on the base member, a plate embedded in the upper face of said disk and rotatably movable therewith, said plate provided with 55 key-ways, key members on the rotary spindle that engage said key-ways for rotating the disk, a metallic plate embedded in the lower face of the insulated disk and rotatably movable with said disk, segments of said metallic 60 plate extending outside the periphery of the disk, and spring contact members connected with the binding posts arranged to make and break contact with the extending segments when the disk and plates are rotated. 65

3. An electric switch comprising a base member having a cover member attached thereto, a rotary spindle mounted in said base and cover, a disk of insulating material mounted on said spindle and having recesses 70 in its upper and lower faces, a plate seated in the upper recess of said disk and keyed thereto, a coiled spring bearing on said plate and on the interior of the cover, a metallic plate seated in the lower recess of 75 the insulated disk and rotatably movable therewith, segments of said metallic plate extending outside the periphery of the disk, projections on the spindle that engage grooves in the upper plate whereby the disk 80 and plates carried thereby are rotated, and contact members attached to the base by binding posts and arranged to make and break contact with the extending segments of the metallic plate when said plate is 85 rotated.

In testimony whereof I affix my signature.
EVALD O. ENGELKE.
